UNITED STATES PATENT OFFICE.

JOHN ROGGINGER, OF CHICAGO, ILLINOIS.

EXTENSION-TABLE.

1,335,859.

Specification of Letters Patent.

Patented Apr. 6, 1920.

Application filed October 27, 1919. Serial No. 333,845.

To all whom it may concern:

Be it known that I, JOHN ROGGINGER, citizen of the United States, residing at Chicago, in the county of Cook and State of Illinois, have invented certain new and useful Improvements in Extension-Tables; and I do hereby declare the following to be a full, clear, and exact description of the invention; such as will enable others skilled in the art to which it appertains to make and use the same.

This invention relates to improvements in extension tables and more particularly to slides for tables of this character, the particular object of the invention being to provide slides which are simple, cheap and durable, and at the same time are equipped with antifriction devices to insure their easy and free operation at all times.

The invention relates more particularly to metallic slides for tables of this character which will not swell, warp or become otherwise distorted and consequently difficult of operation.

The invention consists in the features of construction and combination of parts hereinafter fully described and particularly claimed.

In the accompanying drawings illustrating a suitable embodiment of the invention

Figure 1 is a top plan view partly broken away showing a table equipped with slides constructed in accordance with the invention.

Fig. 2 is a fragmentary detail side elevation of the same.

Fig. 3 is a vertical transverse section on the line 3—3 of Fig. 1.

Fig. 4 is a fragmentary detail longitudinal section on the line 4—4 of Fig. 1.

Fig. 5 is a detail perspective view partly in section showing the slides.

Referring now to said drawings, 1 and 2 indicate the separable portions of the table top, and 3 indicates the top plate of the pedestal 4 upon which the table top is mounted. Secured to the ends of the plate 3 are two oppositely channeled rails, each comprising a pair of opposed channels 5 and 6, the middle portions of which are disposed back to back and are separated from each other by an open space into which the standards 7 project, the latter being secured to the middle portions of the opposed channels 5 and 6 in any suitable manner. Each of the standards 7 includes a brace member 8 se-

cured to the horizontal flange 9 of the channel bar to the other flange 10 of which the lower end of the standard 7 is secured, said channels being mounted on the upper end 60 corners of the plate 3. Mounted in the end portions of the open space between the opposed channels 5 and 6 are two supporting members 10 provided with L-shaped flanges 11 carrying studs 12 on which flanged anti-friction rollers 13 are rotatably mounted.

Secured to the lower face of the member 1 of the top plate and similarly to the member 2 thereof are two angle strips 14, each flange of which is provided with a channeled lip 15. Each of the angle strips 14 is secured only at one end portion to one of the table top members and projects normally underneath the other thereof. The vertical flange of each of the channel strips 14 opposes one of the channels 5 and 6 and carries a plurality of studs on which anti-friction rollers 16, 17 and 18 are rotatably mounted. The said rollers 16, 17 and 18 are of a diameter greater than the mouth portions of the channels 5 and 6 in which they are adapted to be received, thus holding the angle strips 14 against lateral movement relatively to the channels 5 and 6. The flange rollers 13 are disposed to support the lower edges of the vertical flanges of the angle strips 14, and the flanges of said rollers are disposed to engage the lips 15 at the lower edges of said vertical flanges to firmly support said angle strips when the table top 90 members 1 and 2 are separated so that the rollers 18 leave the ends of the channels in which they are engaged, thereby preventing sagging of said table top members in their extended positions.

My said table slides are particularly adapted to be used on extension tables equipped with suitable stops for limiting the outward movement of the members 1 and 2, such means being particularly illustrated 100 and described in my copending application for Letters Patent for extension tables Ser. No. 179099 filed July 6, 1917, or any other means such as a flexible element or other coacting stops which are well known in the art and, therefore, are not herein particularly described as constituting no part of the present invention.

The construction as herein illustrated and described permits the use of relatively light 110 sheet metal for the construction of slides

of sufficient strength and durability to bear the strains and stresses to which they are subjected in use with the minimum weight of material employed. This is due to the 5 specific construction of the several elements of the slide and also to the use of the rollers 13 disposed in supporting relation to the rails carried by the table top members for affording the latter firm support at the 10 extreme ends of the members rigidly mounted on the pedestal or other support for the table top.

It will be understood, of course, that in the accompanying drawings I have shown 15 only the preferred embodiment of the invention, it being obvious that said embodiment may be changed and varied in details without departing from the invention as defined in the appended claims.

20 I claim as my invention:

1. An extension table comprising a base, a pair of parallel rails mounted on opposite sides of the base each comprising two oppositely disposed channeled members hav-

ing contracted mouth portions, a pair of 25 separable table top members, a pair of rails secured to each thereof and projecting beneath the other, a plurality of antifriction rollers carried by each of said rails and engaging in the respective channels of the rails 30 of said base, and antifriction rollers mounted at the ends of the latter in supporting relation to the rails secured to the table top members.

2. An extension table slide comprising a 35 middle member adapted to be mounted on a rigid support and comprising two channeled elements presenting outwardly facing contracted mouth portions, a rail opposing the mouth portion of each of said channeled 40 elements and equipped with a plurality of antifriction rollers engaging in the latter, said last-named rails being longitudinally movable relatively to the first-named, and antifriction rollers mounted at opposite ends 45 of said first-named rails in supporting relation to the lower edges of the last-named.

JOHN ROGGINGER.
